[57] **CLAIM**

The ornamental design for an electronic educational game housing, as shown and described.

DESCRIPTION

FIG. 1 is a left rear perspective view of the electronic educational game housing, with the lid portion lowered, showing my new design;

FIG. 2 is a left rear perspective view thereof with the lid portion raised;

FIG. 3 is a top plan view thereof with the lid portion lowered;

FIG. 4 is a right rear perspective view thereof with the lid portion raised;

FIG. 5 is a left front perspective view thereof with the lid portion raised;

FIG. 6 is a bottom plan view thereof; and,

FIG. 7 is a fragmentary sectional view of the surface of the convex feature on the lid of the embodiment of FIGS. 1-6, taken along a line perpendicular to the three parallel features on the front portion of the convex feature.
